THE NATIONAL LITHOGRAPHING COMPANY,
WASHINGTON, D. C.

UNITED STATES PATENT OFFICE.

NILS CHRISTIANSON, OF HUNTSVILLE, UTAH TERRITORY.

DANCING TOY.

SPECIFICATION forming part of Letters Patent No. 509,150, dated November 21, 1893.

Application filed March 2, 1893. Serial No. 464,366. (No model.)

To all whom it may concern:

Be it known that I, NILS CHRISTIANSON, of Huntsville, in the county of Weber and Territory of Utah, have invented certain new and

5 useful Improvements in Dancing Toys; and I do hereby declare the following to be a full, clear, and exact description of the invention, such as will enable others skilled in the art to which it appertains to make and use the same.

10 This invention relates generally to toys, and particularly to that class thereof known as dancing toys.

The object of my invention is to provide a very cheap and simple toy, which can be 15 easily constructed, and operated to move a set of dancing figures.

A further object is also to provide for the movement of a musician figure, and also that of a clown.

20 A music box is also connected with the toy, and is operated by the same power that moves the dancers, musician, and clowns.

My invention consists in the details of construction and combination of parts, all of 25 which will be fully described and claimed.

In the drawings forming a part of this specification, Figure 1, is a perspective view of my improved device, and Fig. 2, is a view showing the internal mechanism.

30 In carrying out my invention, I employ a box A, of any suitable size, in which is journaled a horizontal shaft B, said shaft being square in cross section. At one end of the shaft B, is mounted a crank C, for driving

35 the device; and at the opposite end is arranged a crank arm C', which is adapted to move the clown, as hereinafter explained. A vertical shaft D, is journaled centrally of the box, and projects some distance above the

40 top of the same, and upon the upper end of this shaft is mounted a circular platform E, which carries the so called dancers F, F. Within the box a horizontal friction wheel G, is mounted upon the vertical shaft, said 45 wheel G, contacting with a friction wheel G' mounted on the shaft B. By this construction, when the crank C, is moved, the platform E, will be revolved.

H, indicates a jointed figure representing a

clown, and I, is a rod connecting the figure 50 H, with the crank arm C' so that as the crank C, is moved and the platform E, revolved, the clown figure H, will be bent back and forth.

K, indicates the musician figure, carrying a movable arm k, which is operated by means 55 of a wire L, which extends down into the box, and there looped around the square shaft, and as said shaft revolves, the arm k will be moved back and forth, owing to the fact that the shaft is square and the loop round. 60

M, designates a music box arranged in the box A, and operated by means of a belt N, which gets its motion from a band wheel O, mounted upon the shaft B.

The parts being thus arranged, the operation is as follows: The crank C, is turned, and the shaft B, revolved. This causes the platform E, carrying the dancers F, to revolve, and at the same time the clown is bent up and down by crank C', and rod I. The 70 musician's arm is moved by the wire and loop, and while all these operations are taking place, the music box is being played by the endless belt.

Having thus described my invention, what 75 I claim is—

1. In a toy of the class described, the combination, with a box, and square shaft, of the figure having a movable arm, and the wire having a circular loop, substantially as shown 80 and described.

2. An improved toy of the class described, comprising a box, the square shaft, and friction and band wheels, the vertical shaft, carrying a friction wheel, and platform having 85 dancers, a jointed figure, and a rod connecting the shaft and said figure, a figure having a movable arm, and a wire and loop connecting said arm and shaft, a music box, and endless belt, all arranged substantially as shown 90 and described.

In testimony whereof I have signed this specification in the presence of two subscribing witnesses.

NILS CHRISTIANSON.
